AUGUST SCHAUSTEN, OF MICHIGAN CITY, INDIANA.

Letters Patent No. 74,152, dated February 4, 1868.

IMPROVEMENT IN REVOLVING CANNON.

The Schedule referred to in these Letters Patent and making part of the same.

TO ALL WHOM IT MAY CONCERN:-

Be it known that I, AUGUST SCHAUSTEN, of Michigan City, in the county of La Porte, and State of Indiana, have invented certain new and useful Improvements in Breech-Loading Cannon; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to breech-loading cannon, having a series of chambers arranged to rotate in a horizontal plane, and be brought successively in line with the bore of the barrel, as hereinafter explained.

Figure 1 is a top plan view,

Figure 2 a longitudinal vertical section, and

Figure 3 is a bottom plan view of the same.

In constructing my improved cannon, I provide a barrel, A, of the requisite length, and through it transversely, near the breech, I form a rectangular opening, of sufficient size to receive a block, having in it a chamber to contain the charge, as shown in fig. 2, in which e represents the breech of the gun, and B the block, containing the chamber C, located in the opening F. The under portion of the barrel is extended back in rear of the breech e, in the form of a flat bar or plate, P, to form a support for the rotating chambers. Upon this extension is placed a circular plate, E, which passes through the opening F in the barrel A, and upon which is placed an annular breech-block, B, which has a series of chambers, C, arranged radially in it, as represented in figs. 1 and 2. This breech-piece or ring, B, is made of the requisite size to admit of having the chambers C formed in it, and is so located and arranged on the track or plate E as to bring the chambers C exactly in line with the bore of the barrel, when it is turned to the proper position, as represented in fig. 2. Upon the under side of the ring B there is formed a projection, which is fitted into a corresponding recess in the face of the plate E, as represented at m of fig. 2, and which serves to hold the ring B in place, and enable it to be turned with facility. In large guns the ring B will be turned by means of a crank and pinion, arranged in any suitable manner. To a projection, n, attached to the rear end of the barrel, on its upper side, is pivoted a lever, l, to the lower end of which is attached a rod, h, for operating it. To this lever l is pivoted a lock-bolt, e, arranged to extend through the breech e, and enter a hole in the ring B, by which the latter is secured in place whenever a chamber, C, is brought in line with the bore, as shown in fig. 2. Below the locking-bolt e, and opposite the centre of the rear end of the chamber C, is placed the firing-pin or needle o, which is also pivoted to the lever l, a spiral spring on either the bolt e, or the pin o, or both, serving to force them forward with sufficient force to explode the charge.

In using my gun, I propose to employ cartridges having fulminate located at the centre of their base, to be penetrated by a needle, like the Prussian rifle; or, a cartridge-case having the fulminate placed therein, as in the central-fire metallic cartridges, to be ignited by a blow from the firing-pin, as may be most expedient in practice. Any suitable gas-check may also be arranged in the chamber C, to close the joint between the ring B and the barrel at the time of firing. If preferred, the chambers need not extend entirely through the ring B, but may have their inner or rear ends left closed. By this plan it will be seen that the recoil is borne by the breech e, which is formed solid with the barrel, and thus the ring or block B is held securely and firmly in place. The cartridges can be inserted as the ring B is being rotated, and thus the gun can be loaded and fired with great rapidity.

Having thus described my invention, what I claim, is—

1. A cannon consisting of the barrel A, having the annular block or ring, B, with the chambers C formed therein, arranged to rotate through an opening in the barrel, as described.
2. The combination of the lever l, locking-bolt E, firing-pin o, and handle h, arranged to operate substantially as set forth.

AUG. SCHAUSTEN.
